J. PIETZUCH.
SHOE HEEL CUSHION.
APPLICATION FILED NOV. 16, 1917.

Patented Feb. 25, 1919.

FIG. 1

FIG. 2.

FIG. 3.

INVENTOR.

Joseph Pietzuch
By John W. Schell
ATTORNEY.

UNITED STATES PATENT OFFICE.

JOSEPH PIETZUCH, OF CINCINNATI, OHIO.

SHOE-HEEL CUSHION.

1,295,201.

Specification of Letters Patent. Patented Feb. 25, 1919.

Application filed November 16, 1917. Serial No. 202,411.

To all whom it may concern:

Be it known that I, JOSEPH PIETZUCH, a citizen of the United States, residing at Cincinnati, in the county of Hamilton and 5 State of Ohio, have invented certain new and useful Improvements in Shoe-Heel Cushions, of which the following is a specification.

My invention relates to heels for boots and 10 shoes and more particularly to a cushion tread therefor, made in composite form of sections, suitably disposed throughout the tread area of the heel, said sections having varying density of material that the sections 15 will vary in degree of resiliency or be more or less yieldable.

In walking, the back outer part of the tread receives the first impact, stress or strain from the foot and the weight supported thereby, and then as the step continues or progresses the strain or weight rolls forward to the inner forward edge of the heel and when the full weight of the 25 body is brought on the heel the weight is distributed throughout the heel.

The foot arch must be properly and uniformly retained in its natural or normal contour or trouble and foot ailments will result. The object of my invention is to 30 form a shoe heel cushion which will properly support the foot and provide comfort and ease in walking, and keep the arch in normal condition and contour by taking care of the strains first and last imparted to the 35 heel in walking. In order to evolve a heel or heel cushion of this kind and character I form a heel cushion of two parts of rubber or analogous material, both placed transversely across the heel, one at the rear part 40 of the heel and one at the forward part thereof, the two parts when made of rubber vulcanized and amalgamated together at their meeting point. To further carry out the invention I make these pieces or sections 45 of varying degrees of resiliency, the outer one softer and more resilient than the inner one, which is made of more density and firmness. The heel cushion is made integral, but of parts as described.

50 It will be noted that the outer or rear surface extends from approximately the central transverse line of the shoe heel backward to the peripheral edge of the heel and the forward portion extends from this line forward

to the inner heel edge, approximately where 55 the foot arch begins.

In the accompanying drawing forming part of this specification:

Figure 1, is a bottom plan view of a shoe, with my new heel cushion shown in position,

Fig. 2, is an isometric view of the heel cushion detached from the shoe, and

Fig. 3, is a longitudinal section taken on line 3—3 of Fig. 1, the sole and upper partly 65 broken away.

The sole of the shoe is marked 1, the leather heel 2 and the upper 3. My new heel cushion is composed of parts, blocks or sections 4 and 5; the nail or screw holes 6 70 and the nails 7 for holding the cushion on the leather heel part 2. The meeting line of the parts 4 and 5 is marked 8. The heel part 4 is made or composed of softer, more yielding and more resilient material than 75 the part 5, which is less yieldable and resili-ent and more firm and stiff.

The part 4 is made of such a degree of resiliency that it will counteract and absorb the initial strain, pressure and shock im- 80 parted by the foot when first set down in walking and as walking progresses and the strain, pressure and shock are transferred more upon the part 5 at the forward part of the heel where more resistance is necessary 85 and the less degree of resiliency needed, as, at this latter point, toward the inner edge, the foot arch begins and therefore the sup- port must be firm to maintain the arch of the foot where it begins in a well supported 90 position. It will be seen from the construc- tion of my cushion heel tread that the strain will be properly and evenly distributed as the heel rolls in walking, from the back edge 95 of the heel to its forward edge.

This style of cushion heel, made accord- 100 ing to my invention is for general use and especially applicable where the arch of the foot has not been affected, or only slightly so, and it is desired to maintain the arch in a practically normal condition.

The parts 4 and 5 may be relatively greater or less in size as needed or found practical in use.

My new heel cushion will wear evenly and 105 thus remain in a position to always main- tain normal walking action and keep the foot in proper poise in the shoe.

By using my new foot heel cushion ailments of the foot are relieved and with persons who step on the back edge of the heel very hard it is an absolute necessity to 5 properly guide the arch of the foot.

What I claim as new and my invention and desire to secure by Letters Patent is:

A rubber heel cushion composed of a forward and a rear section made integral and 10 forming the tread area of the heel, said cushion made of rubber material, the said sections divided by a transverse line approximately near the middle of the heel, the

rear section lying back of said line and the forward section lying in front of said line, 15 the rear section being softer and having a greater degree of resiliency than the forward section which is harder and less resilient.

In testimony whereof I affix my signature 20 in the presence of two witnesses.

JOSEPH PIETZUCH.
